UNITED STATES PATENT OFFICE.

HARRY R. CANFIELD, OF CLEVELAND, OHIO, ASSIGNOR TO THE ELECTRIC CONTEROLLER
AND MANUFACTURING COMPANY, OF CLEVELAND, OHIO, A CORPORATION OF OHIO.

ELECTRIC SWITCH.

1,214,752.

Specification of Letters Patent.

Patented Feb. 6, 1917.

Application filed February 9, 1911. Serial No. 607,560.

To all whom it may concern:

Be it known that I, HARRY R. CANFIELD, a citizen of the United States, residing at Cleveland, in the county of Cuyahoga and State of Ohio, have invented new and useful Improvements in Electric Switches, of which the following is a specification.

My invention relates to electric switches of the magnetically-operated types.

10 The objects thereof are to provide a self-contained switch of this type which will not close its contacts so long as the current flowing through its actuating winding is above a predetermined value; to provide a switch of this character in which the amount of the current necessary to prevent the actuation of the same may be changed at will; and to provide a switch which has but few parts and is cheap to construct. Other objects 20 will appear hereinafter.

Referring to the accompanying drawing, Figure 1 is a vertical section showing one form of the present invention, parts being shown in side elevation. Fig. 2 is a front elevation thereof.

On the drawing, 1 is an insulating base to which I secure the magnet frame 2 of magnetic material, such as cast-iron. This frame may be made in various shapes, but I have 30 shown it with the upper and lower arms or poles 3 and 4.

5, 5 are the stationary contacts which are secured to the base 1, and 6 is the movable contact which is shown connected to the 35 upper end of the vertical reciprocating rod 7 made preferably of non-magnetic material. To the lower end of the rod 7 I secure the plunger or armature 8 composed of magnetic material, such as soft steel. I provide 40 the armature 8 preferably with an extension 9 of preferably smaller cross-area than that of the armature, which extension may be made integral with the armature. The extension 9 is provided with the non-magnetic 45 separator 10 which I show in the form of a sleeve secured thereto. The extension 9 with the separator 10 thereon reciprocates in an opening through the arm 4, and the rod 7 reciprocates through the plug 11 seated in 50 an opening in the arm 3, the plug being provided with the shoulder 12 which normally rests on the top of the arm 3 and limits its downward movement. The contact 6 rests on the top of the plug 11 when it is in its

normal unoperated position which is that shown on the drawing.

The parts are so proportioned that, when the contact 6 is in its unoperated position there is an air-gap 13, which I call the lock-out gap, between the lower end of the armature and that part of the arm 4 surrounding the separator 10, the said part of the arm 4 being preferably elevated above the other part of the arm 4 to present an annular boss 14. The top of the armature 8 is separated 65 from the arm 3 by the air-gap 15, which I call the operating gap.

Between the arms 3 and 4 and surrounding the armature 8 is the winding 16, provided with the terminals 17 and 18. The 70 winding is made adjustable longitudinally of the armature, by the following means. The lower end of the winding 16 rests on the ends of the screws 19 which work in threaded holes in the arm 4 and the upper 75 end of the winding is engaged by the ends of the screws 20 which work in threaded holes in the arms 3. 21 are jam nuts for preventing the screws 19 and 20 from accidentally turning.

The apparatus described involves the 80 principles of the switch shown in my applications, Serial Number 583,000 filed September 21, 1910, and Serial Number 604,381, filed January 23, 1911. In the said applications I show a means for adjusting the 85 length of the lower or lock-out air-gap 13. In the present application I accomplish the same results, by adjustment of the winding 16 as I accomplish by adjusting the length of 90 the lock-out air-gap of my said prior application.

If the winding 16 is energized above a definite or predetermined value, the weight 95 of the plunger and the parts movably connected thereto together with the magnetic pull in the lock-out gap 13, that is, between the armature 8 and the pole 4, is greater than the magnetic pull in the opposite direction in the operating gap 15, that is, between the 100 armature 8 and the pole 3, thereby causing the armature and the contact 6 to remain unactuated, as shown on the drawing. If the excitation of the winding be diminished to the said value, the magnetic pull on the 105 armature will predominate in the operating gap 15, causing the armature to move toward the pole 3 and the contact 6 to engage the

contacts 5. After the armature has been actuated as described, the gap 15 is reduced so that the armature 8 will remain in its actuated position with a very small amount 5 of excitation in the winding 16. If the current in the winding 16 is initially below the amount required to prevent the actuation of the armature, which amount of current may be termed the lock-out value, the armature 10 will be actuated, that is, moved toward the pole 3, provided the current in the winding 16 is at or above a minimum value, which is just sufficient to actuate the armature.

By raising the winding 16 I raise the lock-out value, that is, the value of the current in 15 the winding which will prevent the actuation of the armature, or lock open the contacts of the switch; conversely, by lowering the winding, I lower the said lock-out value 20 of the energizing current necessary to lock out the armature and parts carried thereby.

I do not limit myself to any definite means for adjusting the winding lengthwise 25 of the armature; in fact, it is essential only that the winding and the armature be relatively movable. I do not limit myself to the precise details and combinations shown since they may both be varied without departing 30 from the spirit of my invention.

I do not limit myself to any theory of the 35 operation of my invention. The magnetic flux appears to flow in a divided path in a part of the magnetic circuit, when the winding is energized. Supposing the magnetic flux to flow from the arm or pole 3 across the gap 15, it would travel along the armature or plunger 8 to the bottom thereof, where it would divide into two paths, one path being 40 through the extension 9 to the arm or pole 4, and the other path being through the gap 13 to the arm or pole 4, where the two paths unite, the flux from the two paths passing along the back of the frame 2 to the arm or pole 3. The flux flowing across the gap 15 produces a force tending to raise the armature; the flux through the gap 13 produces a 45 force tending to prevent the armature from being raised. When the winding is excited at a low or an operating value, the larger 50 part of the magnetic flux produced thereby will flow through the extension 9, which will have no tendency to prevent the armature

from rising, the magnetic flux in the gap 13 being too small to overcome the pull of the magnetic flux in the gap 15, through which 55 the entire magnetic flux flows. When the winding is excited at a high or lock-out value, the restricted area of the magnetic circuit in the extension 9 forces more magnetic flux to pass into the pole 4 by way of the air-gap 13, thereby increasing the force tending 60 to prevent the upward movement of the armature. The parallel, or divided, paths for the magnetic flux may be variously constructed and located so long as the flux in 65 one path prevents the operation of the armature or other moving element by the flux in another part of the magnetic circuit upon the excitation above a predetermined value 70 of the winding generating the magnetic flux. If a magnetic flux is generated and applied in any manner to prevent the actuation of the armature or its equivalent, provided the exciting winding is energized above a predetermined value, and if the winding and the 75 armature have relative adjustment that changes the lock-out value of the current necessary to prevent the operation of the armature, the same will embody the principles of the invention covered by this application.

I claim—

In an electro-magnetic switch, a switch contact, a movable member of magnetic material, a second switch contact movable 85 thereby into engagement with the first-named contact, a magnetic circuit including the movable member, a winding for magnetizing the circuit, there being a gap in the circuit adjacent to each end of the movable 90 member, a magnetic shunt around one of the gaps for preventing the operation of the movable member to close the switch by current in the winding above a predetermined value, and means for adjusting the winding 95 in the direction of its axis to vary the relation of the magnetic pulls at the gaps.

Signed at Cleveland, Ohio, this 30th day of January, A. D. 1911.

HARRY R. CANFIELD.
